UNITED STATES PATENT OFFICE.

HENRY GIBSON O'NEILL, OF NEW YORK, N. Y., ASSIGNOR OF TWENTY-NINE THIRTY-SECONDS TO JOHN ROONEY, OF SAME PLACE, AND ALEXANDER ARNOIS, OF PHILADELPHIA, PENNSYLVANIA.

ELECTROTHERAPEUTIC APPARATUS.

SPECIFICATION forming part of Letters Patent No. 628,351, dated July 4, 1899.

Application filed October 15, 1898. Serial No. 693,681. (No model.)

To all whom it may concern:

Be it known that I, HENRY GIBSON O'NEILL, a subject of the Queen of Great Britain, and a resident of New York, in the county of New York and State of New York, have invented 5 certain new and useful Improvements in Electrotherapeutic Apparatus; and I do declare the following to be a full, clear, and exact description of the invention, such as will enable 10 others skilled in the art to which it appertains to make and use the same, reference being had to the accompanying drawings, and to letters of reference marked thereon, which form a part of this specification.

15 Figure 1 of the drawings is a longitudinal vertical section of the cabinet. Fig. 2 is a horizontal section of the same.

This invention appertains to the art of electrotherapeutics, and is designed to furnish a 20 means whereby tissue activity, elimination, and the various physiological functions and reparative processes of nature may be stimulated.

The principle involved consists in subjecting 25 the nude body to powerful actinic rays of light and oscillating electric currents of rapid alternations, preferably approaching the sine curve, in the presence of an atmosphere of nascent ozone.

30 The process is carried out by the following apparatus:

Fig. 1 represents a cabinet in cross-section, (lettered A,) its dimensions being usually 35 about six feet high, seven feet long, and four feet wide. Its interior walls are insulated, and at one end it has a door D. At a convenient distance from the floor is an insulated support D', preferably of a translucent or transparent material. Suspended from the 40 ceiling or top of the cabinet are adjustable chandeliers E with reflectors E', containing electric lights adapted to burn with a high degree of incandescence for the purpose of producing actinic rays of light. Supported 45 from the floor of the cabinet is a similar arrangement of lights F, both the upper and lower ones being arranged in groups or sections and any group or section of those above and below being capable of being adjusted 50 so that they may be brought nearer to or re-

moved farther from the person to be treated, who reclines upon said support. Conveniently arranged so that the hands or the feet may rest against them are vacuum-electrodes II, of glass, suitably attached to the insulated 55 walls of the cabinet. These electrodes are connected in series, and one of the terminals is connected with a source of high-tension currents of electricity, the last electrode being without return connection. Toward the 60 top of the cabinet there are attached to the walls of the same two metallic electrodes, one being a rod with a sharp point and the other a ring, each being connected with a different pole of a high-tension-current generator. 65 These electrodes (marked, respectively, C and C') are so arranged as to produce such a spark-gap as may be desired or necessary.

The system of treatment is as follows: The patient reclines on the support aforesaid 70 (marked D') and is subjected to the action of the actinic rays of light that penetrate the body in all directions, while currents of high tension and high frequency are passed through the body. The patient is also during 75 this operation surrounded by an atmosphere of nascent ozone, produced by the passage of the current between the metallic electrodes C and C'. The pathological effects of this treatment are great stimulation of tissue activity, 80 elimination of the poisonous fluids of the body, inspiration of ozonized air through the pores of the skin and inhalation through the lungs, suboxidation of waste matter and micro-organisms in the system, and elimination 85 of large quantities of CO₂ and urea. In addition this treatment tranquilizes the nervous system, instantly allays pain, and stimulates the digestive functions.

I am aware that light has been employed 90 for pathological purposes. Alone, however, its effect is very limited. By the combination of actinic rays of light in conjunction with harmonic currents of electricity administered through the vacuum-electrodes of glass all 95 unpleasant physiological effects are removed, and combined with the stimulating and anti-septic qualities of an atmosphere of nascent ozone the results obtained in actual practice are, to say the least, remarkable.

The electrodes II herein referred to form the subject-matter of a separate application filed by me, Serial No. 693,682.

Having thus described my invention, what I claim as new, and desire to secure by Letters Patent, is—

- 5 1. In therapeutic apparatus, the combination with means for supporting the body in convenient position for treatment, of means for directing upon the body actinic rays of light, means for applying to the body oscillating electrical currents of high tension, and means for producing around the body an atmosphere containing nascent ozone, substantially as specified.
- 10 2. The combination in electrotherapeutic apparatus, of an inclosed chamber having insulated walls; a support therein; vacuum-electrodes of glass, and metallic electrodes so arranged as to produce a decomposing action on
- 15
- 20

the atmosphere when connected with a source of high-tension current, substantially as and for the purpose set forth.

3. The combination in electrotherapeutic apparatus, of an inclosed chamber, a transparent or translucent support therein, vacuum-electrodes of glass adjacent to the support, metallic electrodes arranged in said chamber so as to produce a decomposing action on the atmosphere when connected with a source of high-tension current, and incandescent lights also adjacent to the support, substantially as specified.

In testimony whereof I affix my signature in presence of two witnesses.

HENRY GIBSON O'NEILL.
